UNITED STATES PATENT OFFICE.

JULIUS L. HANSON, OF NEW YORK, N. Y.

DESIGN FOR A PUZZLE-BOX.

SPECIFICATION forming part of Design No. 26,705, dated March 2, 1897.

Application filed December 22, 1896. Serial No. 616,666. Term of patent 14 years.

To all whom it may concern:

Be it known that I, JULIUS L. HANSON, of New York, county and State of New York, have invented a new and original Design for a Puzzle-Box, of which the following is a specification.

This invention relates to a new and original design for a puzzle-box, which is fully represented in the accompanying drawings.

- 10 Figure 1 is a plan view of my design. Fig. 2 is a cross-section thereof on the line xx , Fig. 1.
- 15 Referring to the drawings, A represents the square frame or border of the design, within which are inclosed the several parts or members.

Commencing at the left upper corner of the frame A is seen the outline of triangular member 1, extending to the right upper corner, thence downwardly to the acute angle of the 5 smaller triangular member 3, and thence upwardly diagonally to the place of beginning. Upon the surface of this member at the left side are seen the representations of three stars and portions of two others in a horizontal line, below which are portions of two other stars, and portions of two other stars in the right corner.

Commencing at the lower angle of member 1 is seen the outline of triangular member 2, 10 which extends diagonally upward as far as the obtuse angle of member 3, thence downwardly to the bottom of member 3, and thence in a straight line to the place of beginning, and upon the face of said member 3 are the 15 representations of three stars and a portion of two others and in the upper corner portions of two other stars.

The outline of the irregular angular figure "2" fills the space between the members 1, 20 3, 4, 5, and 6 and the border, and has upon its face the representation of a bird with partly open wings holding a scroll in its beak and portions of two stars.

The outline of the square rectangular member 4 extends in a line parallel with member 3, to the upper corner of member 5, thence downwardly to the border, thence to the right corner of the border, and thence upwardly to the place of beginning, and has upon its left 5 side the representation of five stars in a perpendicular line and five parallel longitudinal

strips of equal width. The outline of the narrow rectangular member 5 extends in a line parallel with member 2, thence downwardly to member 6, parallel therewith to 55 member 4, and thence upwardly to place of beginning, and upon its face is the representation of a star.

The outline of the rectangular member 6 extends from a line parallel with the bottom of member 2 to the border, thence downwardly as far as member 7, thence in a line parallel with member 2 to member 5, and thence to the place of beginning, and upon its face is seen the representation of a star. 65

The outline of member 7 extends in a line parallel with members 5 and 6 as far as the border, thence downwardly to member 8, thence to member 4, and upward to place of beginning, and bears upon its face the figures 70 of two stars.

The outline of member 8 extends in a line parallel to member 7 to the border and embraces the space between members 4 and 7 and the border, and has upon its surface the 75 representation of six stars arranged in vertical lines of three each.

The various members will have colors applied upon their surfaces, as follows: 1, 3, 5, 6, 7, and 8 will have a background of blue, 80 and the stars will be white. The border of member 4 will have blue and the stars white, with the top, center, and bottom stripes red and the other two white. Member 1 will have a blue ground with white stars and the letters in red. Member 3 will have a blue ground, white stars, a white field, and the figure of the bird thereon black.

Having thus described my invention, what I claim as new, and desire to secure by Letters 90 Patent, is—

The design for a puzzle-box as herein shown and described.

In testimony that I claim the foregoing as my invention I have signed my name, in presence of two witnesses, this 21st day of December, 1896.

JULIUS L. HANSON.
